JOSEPH A. SANDFORD, JR., OF EAST LIVERPOOL, OHIO, ASSIGNOR TO R. THOMAS AND SONS COMPANY, OF EAST LIVERPOOL, OHIO, A CORPORATION OF OHIO.

INSULATOR.

1,093,480.

Specification of Letters Patent. Patented Apr. 14, 1914.

Application filed June 13, 1912. Serial No. 703,487.

To all whom it may concern:

Be it known that I, JOSEPH ADDISON SANDFORD, Jr., a citizen of the United States of America, residing at East Liverpool, in the county of Columbiana, State of Ohio, have invented certain new and useful Improvements in Insulators, of which the following is a specification.

My invention relates to insulators, and particularly to insulators of the built-up type, such, for instance, as that described in my copending application, Serial No. 666,273, the object of my present invention being to improve the same in the features herewith disclosed.

In the accompanying drawings Figure 1 is an elevation half in section, of an insulator in which my improvement is embodied in one form; Fig. 2 is a similar view of a detail drawn to an enlarged scale.

It has been found in assembling the interchangeable insulator units described in my copending application above mentioned, that it is extremely difficult to apply the cementing medium between the units in uniform quantity and thickness, with the result that the units are consequently spaced unequally apart. Further, until the cement has set, there is a tendency for the units, which are of considerable weight, to displace the cement, squeezing part into the head of the bell and part out at the open end, with the result that the units settle together and the insulator as a whole loses some of its height, and consequently some of its capacity. Again, inasmuch as the cement contains a certain proportion of moisture when it is applied, and inasmuch as the air chamber between the heads of the juxtaposed units is open to the joint, the air in the chamber takes up moisture from the cement and the electrostatic capacity of the insulator is to a certain extent diminished by reason of the presence of this damp air in the air chamber. These various defects are now substantially eliminated by the use of spacing plugs of the character herewith illustrated. In the particular form shown, which is of course merely an exemplary embodiment of my invention, this spacing plug takes the form of a disk 5, the periphery of which is offset at 6 to form a shoulder, while the remaining portion 7 is preferably beveled to the incline of the inner face of the bell insulator B with which it is to be used.

Recesses 8 and 9 may be formed in the opposite faces of the plug, if desired.

In building up an insulator of this type, the first bell unit B, having been fitted in the cap unit A, both being inverted, a plug 5 is inserted in the unit B, until it reaches a point of such diameter that it is wedged in position. The diameter of the plug is so predetermined that upon the insertion of the head of the next bell unit B, the latter when resting upon the plug, is peripherally spaced the desired distance from the inner face of the bell so as to admit a suitable amount of cement b. Inasmuch as the units B are uniform and interchangeable in this particular type of insulator, it is obvious that the next plug 5 spaces the next unit B a like distance from the superposed unit, and so on throughout the height of the insulator. Consequently a uniformity of construction and of capacity is obtained with a certainty not otherwise possible. Furthermore, the plug has a secondary result by no means unimportant, viz., the exclusion of cement and its moisture from the air chambers C between the heads of the respective units. The cement b which is applied while the parts are in inverted position, is halted by the shoulder 6 and has no opportunity to enter the air chamber or to moisten the air therein. Again, the plug adds to the mechanical strength of the joint between the units.

Obviously the plug may be made of any desired material, although preferably of porcelain or other non-conductive, in order to prevent the condenser action which would take place were metal employed. The utility of the plug is not limited to the particular type of insulator illustrated but it may be employed in built up insulators of any suitable character.

I claim as my invention,

1. A built up insulator having nested units, in combination with a plug disk peripherally engaged and supported within the head of one unit and serving to space the succeeding unit from the latter and prevent the entry of cement into the space between the heads of juxtaposed units.

2. A built up insulator having nested units, in combination with a plug disk wedged within the superposed unit for spacing the succeeding nested unit therefrom.

3. A built up insulator having nested

units spaced apart, an imperforate spacing plug disk serving as spacing means and having its periphery beveled to the incline of the inner face of the insulator unit with which it is designed for use.

4. A built up insulator having nested units spaced apart, an imperforate spacing plug disk serving as spacing means and having its periphery shouldered and beveled to

the incline of the inner face of the insulator unit with which it is designed for use.

In testimony whereof I have signed my name to this specification, in the presence of two subscribing witnesses.

JOSEPH A. SANDFORD, JR.
